UNITED STATES PATENT OFFICE.

LEANDER M. HOSKINS, OF MADISON, WISCONSIN.

WINDMILL.

SPECIFICATION forming part of Letters Patent No. 274,329, dated March 20, 1883.

Application filed January 26, 1883. (No model.)

To all whom it may concern:

Be it known that I, LEANDER M. HOSKINS, of Madison, in the county of Dane and State of Wisconsin, have invented a new and useful Improvement in Windmills; and I do hereby declare that the following is a full and exact description of the same, reference being had to the accompanying drawings, and to the letters of reference marked thereon.

10 My invention relates to an improvement in windmills, its object being to furnish means for gearing windmills, so that power may be transmitted from the wind-wheel shaft to the machinery to be driven independently of the motion of the turn-table.

15 To the accomplishment of the above the invention consists in the employment of a secondary or compensating turn-table revolved by and with the main turn-table; and, further, 20 in the novel construction and arrangement of certain other parts, all as will be hereinafter fully described and claimed.

25 In order that those skilled in the art to which it pertains may understand my invention, I will now give a detailed description of the same, making frequent reference to the accompanying drawings, which form part of this specification, and in which—

30 Figure 1 is a view partly in perspective and partly in section, and in which the principal features of my invention are shown; Fig. 2, a similar view, showing a modification of the construction shown in Fig. 1; and Fig 3, a view in detail, showing the manner of connecting certain parts of the device.

35 Like letters refer to corresponding parts in the several views.

In the drawings, A represents the wind-wheel shaft, which has bearings in a suitable 40 box or casing, A', said casing being mounted upon a support, A². This support A² is firmly secured at its lower end to the main turn-table K, which will be hereinafter referred to, and through its medium said turn-table is revolved whenever the position of shaft A is changed by a change of wind.

45 Upon the outer end of shaft A a suitable wind-wheel (not shown) is mounted, and to the inner end of said shaft a bevel-gear wheel, B, is keyed. In its revolution the gear-wheel B meshes with a similar wheel, C, keyed, as shown, to a vertical shaft, D, which is situated on the

center line of turn-table K. Secured to the shaft D is a second gear-wheel, E, which in its revolution meshes with a gear-wheel, F, 55 keyed to the upper end of a shaft, G. The shaft G has bearings in the compensating turn-table marked H, and passes obliquely downward to the center line of the tower, where it is coupled by means of a universal joint, M, 60 to a vertical shaft, N, said shaft N connecting in any suitable manner with the machinery to be driven.

The main turn-table K is formed of any suitable material, and consists of a cylinder with 65 inwardly-projecting flanges at its upper and lower ends. The turn-table thus formed is of such a size that it will encircle the tower-casting L and revolve about the same. As before mentioned, there is an upwardly-projecting arm or support, A², which connects this turn-table with the casing in which the wheel-shaft has its bearings.

The tower-casting L, above referred to, has at its upper end an outwardly-projecting flange 75 situated between the inwardly-projecting flanges of the turn-table K, above described. This flange is of such a shape as to form suitable paths for the friction wheels or rollers I. Of these rollers there are two sets or series. 80 Those of the upper set are carried upon journals fixed to the compensating turn-table H at its circumference, and those of the lower set are carried in a like manner upon journals fixed to a ring, H', made for the purpose. This 85 lower set of rollers are employed for the purpose of enabling the turn-table K to swivel easily upon the tower-casting. As shown in the drawings, the main turn-table K rests upon the upper set of friction-wheels, and is of 90 such a depth that its lower flange will press against the lower set of such wheels. The compensating turn-table H is, as shown, smaller than the main turn-table K, and revolves within said turn-table. The parts being constructed 95 and arranged as thus far described, it will be apparent that upon the revolution of turn-table K the frictional contact between said turn-table and rollers I will cause the compensating turn-table H to revolve with exactly 100 half the angular velocity of turn-table K.

In Fig. 2 of the drawings I have illustrated a modified construction and arrangement of the means for revolving the compensating turn-

table. As shown in that figure, the two turn-tables are arranged the one below the other. Each of the turn-tables K and H is provided on its circumference with a series of gear-teeth, 5 which engage with pinions O and R, mounted respectively upon the upper and lower end of a vertical shaft, P, said shaft having bearings in suitable brackets secured to tower-casting L. By means of this construction it will be 10 seen that upon the revolution of turn-table K pinion O is revolved, and with it the shaft P and pinion R, motion being imparted to turn-table H through the medium of said pinion R.

It will be apparent that many other constructions might be employed to impart motion to the compensating turn-table; but it will not be necessary to particularly describe such constructions.

As long as the position of the wind-wheel is 20 not changed by a change of wind the turn-table K and compensating turn-table H will remain at rest, and the operation of the machine will be obvious, power being imparted to the machinery to be driven from the wind-wheel shaft 25 through the medium of the gear-wheels and shafts hereinbefore described. When, however, the wind-currents change, the position of the wind-wheel is changed and the turn-table K is revolved, the gear-wheels C and E 30 being simultaneously revolved by the change in the position of the gear-wheel B, mounted on shaft A.

It will be readily understood that if the compensating turn-table H were stationary, or if the shaft G had its bearing in any other stationary part of the machine, the velocity of said shaft in its revolution would be changed by the change in the velocity of revolution of wheel E, caused by the revolution of turn-table K. When, however, the turn-table K is 40 revolved, motion is imparted to the compensating turn-table H by means of frictional rollers I, and said turn-table H is caused to

revolve at exactly one-half the angular velocity of turn-table K, thus causing the wheel F 45 to move encyclically about the center of the compensating turn-table H, which motion (if the wheels E and F are of equal size) will exactly compensate for the motion of wheel E with turn-table K, the revolution of said turn-table K thus failing to revolve the wheel F about its own axis, as would be the case if the bearing of the shaft G were stationary. It is thus evident that the motion imparted to the driven machinery will not be varied by the 50 revolution of the turn-table, caused by changes in the direction of the wind; but will be as the motion of the wind-wheel shaft.

It will also be apparent that the wheels E and F need not be of the same size; but should 55 they differ in size it will become necessary to change the relative rate of speed of turn-tables K and H.

Having thus described my invention, what I claim as new therein, and that for which I desire to secure Letters Patent, is—

1. In the windmill described, a secondary or compensating turn-table actuated by the movement of the main turn-table, as and for the purpose set forth.

2. In a gearing for windmills, the combination, with the wind-wheel shaft, of shafts D and G, connected by gear-wheels E and F, the parts arranged as shown, and for the purposes set forth.

3. In a gearing for windmills, the combination, with shafts D and G, connected by gear-wheels E and F, of the compensating turn-table H, actuated by the movement of turn-table K, substantially as described and shown.

In testimony whereof I affix my signature in presence of two witnesses.

LEANDER M. HOSKINS.
